DESIGN FOR A COMBINED GIRDLE AND BRASSIÈRE

Mollie Kleinitz, New York, N. Y.

Application May 4, 1945, Serial No. 119,396

Term of patent 7 years

(Cl. D20—2)

To all whom it may concern:

Be it known that I, Mollie Kleinitz, a citizen of the United States of America, residing in New York, county of Bronx, and State of New York, have invented a new, original, and ornamental Design for a Combined Girdle and Brassière, of which the following is a specification, reference being had to the accompanying drawing, forming part thereof.

Fig. 1 is a front perspective view of a combined girdle and brassière showing my new design.

Fig. 2 is a rear perspective view thereof.

I claim:

The ornamental design for a combined girdle and brassière, substantially as shown.

MOLLIE KLEINITZ.
